CASH REGISTER

Merle F. Rath, Granada Hills, and Otis O. Highfill, North Hollywood, Calif., assignors to Telecomputing Corporation, a corporation of California

Application December 21, 1954, Serial No. 33,642

Term of patent 3½ years

(Cl. D64—11)

FIG. 1.

FIG. 2.

FIG. 3.

FIG. 4.

Fig. 1 is a side elevational view of a cash register showing our new design,

Fig. 2 is a rear elevational view thereof,

Fig. 3 is a front elevational view, and

Fig. 4 is a top plan view.

The appearance of the opposite side of the design is substantially similar to the appearance of the side that is shown.

The characteristic features of the design reside in the portions shown in full lines.

We claim:

The ornamental design for a cash register, substantially as shown and described.
